UNITED STATES PATENT OFFICE.

MATHIAS SPORER, OF HARTFORD, CONNECTICUT.

MAGAZINE FIRE-ARM.

SPECIFICATION forming part of Letters Patent No. 320,186, dated June 16, 1881.

Application filed November 22, 1881. (No model.)

To all whom it may concern:

Be it known that I, MATHIAS SPORER, of Hartford, in the county of Hartford and State of Connecticut, have invented certain new and useful Improvements in Magazine Fire-Arms, of which the following is a specification.

This invention has reference to an improved magazine fire-arm of that class in which the magazine is located in the butt of the stock, and in which the cartridges are automatically supplied to the breech of the barrel by the movements of the breech-bolt; and the invention consists of a receiver or shoe at the breech end of the barrel, which is connected by an inclined well and tubular channel with a vertical magazine in the butt of the stock, and with a cartridge-feeding mechanism operated by the reciprocating breech-bolt. The cartridge-feeding mechanism transfers the cartridges successively and automatically into the inclined well, from which they are moved into the breech by the breech-bolt.

The invention consists, further, of certain details of construction and combination of parts by which the breech-bolt is thrown in or out of connection with the cartridge-feeding mechanism, as will more fully appear hereinafter, and finally be pointed out in the claims.

In the accompanying drawings, Figure 1 represents a side elevation of my improved magazine fire-arm. Fig. 2 is a top view of the same. Fig. 3 is a sectional side elevation of the fire-arm drawn on a larger scale, and shown with parts broken away. Figs. 4, 5, 6, and 7 are details of the mechanism for throwing the breech-bolt in or out of connection with the cartridge-feeding mechanism. Fig. 8 is a side elevation of the receiver and the mechanism for establishing connection with the cartridge-feeding mechanism, showing the same in position for single firing. Fig. 9 is a detail vertical longitudinal section of the butt, showing the magazine, and a side view of the cartridge-feeding mechanism. Figs. 10 and 11 are detail vertical longitudinal sections through the butt, magazine, and cartridge-feeding mechanism, showing the latter respectively in position after the cartridge has been thrown forward and immediately before throwing the same. Fig. 12 is a detail horizontal section

through the butt, showing a top view of the cartridge-feeding mechanism.

Similar letters of reference indicate corresponding parts.

A in the drawings represents the barrel; B, the receiver or shoe at the breech end of the same; and C, the sliding breech-bolt, which is accurately fitted to the breech of the barrel. The breech-bolt C is inserted through the rear end of the receiver, and reciprocated in the same in the usual manner. Any approved construction of the breech-bolt may be used, as the same forms no part of my invention. The receiver B is open at the bottom and connected by an inclined well, D, with a tubular channel, D', that extends in backward direction along the bottom part of the stock E and butt E' through the entire length of the latter, as shown in dotted lines in Fig. 1 and in full lines in Figs. 8, 9, 10, and 11. At the middle part of the butt E' is arranged the magazine E'', which extends vertically through the butt, the lower part of the magazine communicating with the corresponding opening at the upper part of the tubular channel D', as shown clearly in Fig. 11. As many cartridges as may be stored in the magazine E'' are supplied to the same by means of a cartridge-holder of suitable construction, (not shown in the drawings,) which cartridge-holder is carried in the cartridge-box and placed in position over the top opening of the magazine, so that all the cartridges in the holder can be quickly transferred to the magazine. The top opening of the magazine is closed by a hinged lid, e, that is provided with a button, e', for conveniently throwing it into open position, and retained by a locking-spring, e'', in open or closed position, as shown in dotted lines in Figs. 1 and 10. The rims of the cartridges are guided along vertical flanges e³ e⁴, arranged at some distance from the rear end of the magazine along both side walls of the same, as shown in Figs. 10 and 11. The flanges e³ e⁴ hold the cartridges in position in the magazine and prevent them from being shifted so as to explode accidentally by concussions imparted to the fire-arm when in use. At the rear end of the tubular channel D' is arranged a fixed guide-spindle, D², which is of a smaller diameter than the channel D'. The spindle D² serves to guide a sleeve, D³, which fills up the space

between the spindle D² and the channel D', and which is acted upon by a strong spiral spring, D⁴, that is interposed between the rear end of the sleeve D³ and a fixed collar, d, at the rear end of the spindle D². The sleeve D³ is made longer at its lower part and shorter at its upper part, as shown in Fig. 11, the upper part abutting, when in forward position, against an upwardly-extending stop, d', at the front end of the spindle D². A slot, d², in the upper shorter part of the sleeve D³ is engaged by a downwardly-projecting lug, d³, of a dog, D⁵, which is pivoted to the rear end of a slide-piece, D⁶, that is guided by a fixed yoke, D⁷, attached to the tubular channel D' immediately back of the magazine, as shown clearly in Figs. 10, 11, and 12, said slide-piece having a slotted opening that registers with the bottom of the magazine E² and with the top opening of the channel D' when the slide-piece D⁶ is in its normal position of rest. The pivoted dog D⁵ has an upwardly-curved and tapering rear end and a convex projection at its top part, which latter is engaged by the free end of a guard-spring, d⁴, attached to the top part of the yoke D⁷. The guard-spring d⁴ serves to press the dog D⁵ down and keep its lug d³ in the recess d² of the sleeve D³. The slide-piece D⁶ is provided at its front end, near the front wall of the magazine, with a pivoted and spring-pressed guard-piece, D⁸, the tapering rear end, d⁵, of which extends laterally across the front end of the slotted opening of the slide-piece D⁶. The guard-piece D⁸ is provided at one side with a downwardly-extending projection or lug d⁶, that is guided along the edge of the side wall of the tubular channel D' when the slide-piece is moved backward or forward, and that is dropped into a depression, d⁷, at the front end of the opening of the tubular channel, as shown in Fig. 10, when the slide-piece D⁶ arrives in its forward position. The slide-piece D⁶ is connected with the breech-bolt C by an intermediate slide-rod, D⁹, the L-shaped rear end of which engages a corresponding rear end at the front end of the slide-piece D⁶, as shown in Fig. 12. The front end of the slide-rod D⁹ engages by a side recess, f, a lateral projection, f', at the rear end of an L-shaped slide-piece, F, the front end, F', of which extends through a side opening, b, of the receiver and, when raised, into the path of a recessed tongue, C', at the side of the breech-bolt C, said tongue having front and rear shoulders, a a', which engage the front end, F', of the slide-piece F, as shown in Fig. 3. The slide-piece F is guided by a longitudinal tongue, f², in a corresponding groove, f³, of an intermediate covering-plate, F², which is pivoted to the rear part of the receiver B, and provided with a rearwardly-extending stop-arm, f⁴, for the rear end, a', of the tongue C' of the breech-bolt. The forward end of the covering-plate F² has a short arc-shaped slot, f⁵, which is engaged by a pin, f⁶, of a thumb lever, F³, that is pivoted at its front end to the receiver B, and provided at its rear

end with a laterally-projecting thumb-rest, f⁷, by which the lever F³ is raised or lowered, according as the cartridge-feeding mechanism is to be thrown in or out of action. By raising or lowering the thumb-lever F³ the covering-plate F², and thereby the slide-piece F, is also raised or lowered, and the front end, F', of the latter thrown in or out of the path of the recessed tongue C' of the breech-bolt C. The front end of the covering-plate F² is provided with a stop-pin, f⁸, that serves to arrest the forward motion of the slide-piece F. When the front end, F', of the slide-piece F is raised, it is placed into the path of the recessed tongue C' of the breech-bolt, as shown in Fig. 4, and the slide-piece F thereby moved backward or forward by the reciprocating motion of the breech-bolt. This motion of the slide-piece F is transmitted by the slide-rod D⁹ to the slide-piece D⁶, which operates thereby the cartridge-feeding mechanism. When the thumb-lever F³ is lowered, the covering-plate F² and slide-piece F are returned into normal position, as shown in Figs. 1, 3, and 8, and thereby the front end of the latter moved out of the path of the recessed tongue C' of the breech-bolt C, in which position the fire-arm is used for single firing. When the covering-plate F² is in normal position, its rear arm, f⁴, projects into the path of the recessed side tongue, C', and serves as a stop for the same when the breech-bolt is pulled back, while, when the covering-plate F² is in raised position for magazine firing, the front end, F', of the slide-piece F serves as a stop for the tongue C', as shown in Fig. 4. The slide-piece F, intermediate plate, F², and thumb-lever F³ are covered by the stock, with the exception of the projecting thumb rest, as shown in Fig. 1. When the slide-piece D⁶ is moved backward by the action of the breech-bolt and the intermediate mechanism, the guard-piece D⁸ is moved along the side wall of the open portion of the channel D', so as to lift the head of the cartridge next above the cartridge at the time in the channel D', as shown in Fig. 11. It causes thereby the separating of the cartridge in the channel D' from the next adjoining cartridge in the magazine, so that the former can be moved forward in the channel D' without being interfered with by the cartridges in the magazine. By the backward motion of the slide-piece D⁶ the sleeve D³ is also moved back by means of the dog D⁵, so that the front part of the sleeve assumes a position back of the rim of the cartridge in the channel D', as shown in Fig. 11. When the sleeve D³ arrives in this position, the dog D⁵ passes over a fixed inclined lug, g, at the upper part of the rear end of the tubular channel, and is lifted by the same, so that its lug d³ clears the slot d² of the sleeve D³, as shown in Fig. 11. Simultaneously therewith the spring D⁴ throws the sleeve D³ forward and impels the cartridge through the channel D' and inclined well of the receiver B into the path of the breech-bolt, which then takes up the cartridge and moves

it forward into the breech and holds it in proper position therein when locked to the breech. The forward motion of the breech-bolt C moves by the intermediate mechanism the slide-piece D⁶ forward, so that the guard-piece D⁸ clears the head of the lowermost cartridge in the magazine and permits the dropping of the cartridge into the open portion of the channel D', ready for the next action of the sleeve D³, which takes place when the breech-bolt is drawn back to its rearmost position in the receiver, in which position uninterrupted communication is established between the breech of the barrel, well D, and channel D'. By the forward motion of the breech-bolt the slide-piece D⁶ and its dog D⁵ are also moved forward, so that the latter is returned into engagement with the slot of the sleeve D³ by the action of the spring d⁴, while the guard-piece D⁸ is returned into its normally-inclined position in front of the bottom opening of the magazine E², as shown in Fig. 10. By the backward motion of the breech-bolt C the firing-pin of the same is set, the same being released by the trigger when in locked position for discharging the cartridge, as customary in bolt-guns.

When my improved fire-arm is used for single firing, the cartridge is inserted directly into the receiver and then moved into the breech by the forward and locking motion of the breech-bolt. The cartridge-feeding mechanism and the slide-piece by which the breech-bolt is thrown into connection with the cartridge-feeding mechanism are in single firing disconnected from the breech-bolt, while for magazine firing the connecting mechanism is thrown into action by raising the thumb-lever F³, whereby the slide-piece F is thrown into the path of the side tongue of the breech-bolt C, so that the connection between the breech-bolt C, slide-piece F, intermediate rod, D⁹, and slide-piece D⁶ is established, and thereby the consecutive automatical forward throwing or impelling of the cartridges from the magazine into the breech of the barrel obtained. The front end of the side tongue, C', of the breech-bolt C is so shaped that it serves as an extractor for automatically throwing out the shells.

The magazine is adapted to store six cartridges, so that the fire-arm can deliver seven shots in succession, including one in the breech. After all the cartridges have been discharged the magazine has to be replenished, which is accomplished by arranging the cartridges in holders containing half a dozen cartridges each, which holders are so constructed that the cartridges can be quickly conveyed from the same without loss of time to the magazine.

The advantages of my improved fire-arm are, first, that the cartridges are supplied successively and automatically from the magazine in the butt by the cartridge-feeding mechanism by the operation of the breech-bolt; secondly, that the fire-arm may be quickly changed from single firing to magazine firing,

or vice versa; third, that the cartridge-feeding mechanism is entirely protected, so that it cannot get out of order; and, lastly, that, owing to the arrangement of the cartridges in the magazine, no accidental explosion of the same by the concussions of the gun can take place.

Having thus described my invention, I claim as new and desire to secure by Letters Patent—

1. In a magazine fire-arm, the combination of a reciprocating breech-bolt, a receiver or shoe having an inclined well, a tubular channel extending from the well to the rear part of the butt, a magazine located in the butt and communicating with said channel, a spring-actuated sleeve, a slide-piece having a spring-pressed dog adapted to engage said sleeve, means for releasing said dog from the sleeve, a slide-rod extending along the channel, a horizontally-guided slide-plate connected to the slide-rod and adapted to be actuated by the breech-bolt so as to release or re-engage the spring-actuated sleeve, substantially as set forth.

2. In a magazine fire-arm, the combination of the butt having a vertical magazine, a tubular channel communicating with the magazine and receiver, a spring-actuated sleeve, a slotted slide-piece, intermediate mechanism connecting the slide-piece with the breech-bolt, a pivoted dog at the rear end of the slide-piece, means for engaging the spring-actuated sleeve by the dog, and means for releasing the same, substantially as set forth.

3. In a magazine fire-arm, the combination of the butt having a vertical magazine, a tubular channel communicating with the magazine and the receiver, a slotted slide-piece, intermediate mechanism connecting the slide-piece with the breech-bolt, a pivoted and spring-pressed guard-piece at the front end of the slide-piece, and a lug on said guard-piece adapted to engage a depression in said tubular channel for raising said guard-piece so as to separate the cartridge in the channel from the next adjoining cartridge in the magazine, substantially as described.

4. In a magazine fire-arm, the combination of the butt, a vertical magazine having guide-flanges for the rims of the cartridges, a tubular channel communicating with the magazine and extending from the same to the receiver, a slotted slide-piece guided in the tubular channel, a dog pivoted to the rear end of the slide-piece, a guard-piece at the front end of the slide-piece, a spring-actuated sleeve adapted to be engaged by said dog, means to release the dog from the sleeve, and means to arrest the sleeve after being released from the dog, substantially as set forth.

5. In a magazine fire-arm, the combination of the butt having a vertical magazine, a tubular channel extending from the magazine to the receiver, a slide-piece having a dog at its rear end, a spring-actuated sleeve adapted to be engaged by said dog, means for releasing the dog from the sleeve, an intermediate slide-

rod, a slide-piece pivoted sidewise of the receiver, a breech-bolt having a recessed side tongue, and means whereby the front slide-piece is thrown in or out of the path of the recessed tongue of the breech-bolt, substantially as set forth.

6. In a magazine fire-arm, the combination of a reciprocating breech-bolt having a recessed side tongue, a pivoted thumb-lever, a pivoted covering-plate operated by said lever, an L-shaped slide-piece guided by said covering-plate and adapted to be raised or lowered thereby, cartridge-feeding mechanism, and a slide-rod connected at one end to the slide-piece and at the other end to said cartridge-feeding mechanism, substantially as described.

7. In a magazine fire-arm, the combination of a reciprocating breech-bolt having a re-

cessed side tongue, a pivoted thumb lever, a pivoted covering-plate operated by said lever, an L-shaped slide-piece guided by said covering-plate and adapted to be raised or lowered by the same, a slide-rod connected to the L-shaped slide-piece, a slide-piece connected to the slide-rod, a dog pivoted to the slide-piece, a guided and spring-actuated sleeve, and means to release the dog from the sleeve, so as to produce the quick forward impelling of the sleeve, substantially as set forth.

In testimony that I claim the foregoing as my invention I have signed my name in presence of two subscribing witnesses.

MATHIAS SPORER.
